(57) **CLAIM**

The ornamental design for a fishing tool, as shown and described.

DESCRIPTION

FIG. 1 is a top right perspective view of a fishing tool showing the claimed design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is top left perspective view of a fishing tool showing the claimed design in an environment in which it may be used.

The dashed broken lines in the figures show portions of the fishing tool or environmental subject matter that form no part of the claimed design. The dot-dash broken lines in the figures show boundaries that form no part of the claimed design. The embodiment of FIGS. 1-7 differs from the embodiment of FIG. 8 only with respect to the orientation of portions of the fishing tool which form no part of the claimed design.
